UNITED STATES PATENT OFFICE.

VICTOR WESTERLUND, OF PORTLAND, OREGON.

FLUE-THIMBLE PROTECTOR.

1,085,311.

Specification of Letters Patent.

Patented Jan. 27, 1914.

Application filed October 22, 1913. Serial No. 796,968.

To all whom it may concern:

Be it known that I, VICTOR WESTERLUND, a citizen of the United States, residing at Portland, in the county of Multnomah and 5 State of Oregon, have invented certain new and useful Improvements in Flue-Thimble Protectors, of which the following is a specification.

This invention pertains to flue thimble protectors, and has for its object to provide 10 a device which may be secured about the thimble of a flue to receive the plaster, and which carries a movable element fitted upon the thimble, permitting the latter to move 15 to a limited extent without disturbing the plaster or injuring the thimble.

A further object is to provide in a device of the kind indicated a movable element 20 which may be fitted upon thimbles of different types, and which will permit the thimble to move the usual distance in settling.

I accomplish these objects by means of the structure illustrated in the accompanying 25 drawing, in which—

Figure 1 is an elevation of the device showing the movable element at its upper limit. Fig. 2 is a vertical sectional view taken on the line X—X of Fig. 1.

30 Describing the drawing in detail, 1 designates a sheet metal plate, in which there is formed a central oblong aperture 4, adapted to expose the flue opening when the plate is in position. At each of the four sides of 35 the plate is formed an extension, or wing 2; and each of these wings is folded inwardly at 3, and again bent outwardly to stand in a plane parallel with that of the main body portion. The first fold 3 is doubled back 40 beyond the point of bending; and the terminal portion is again bent outwardly to form a retaining element to lie flat upon the laths 9 to which they are nailed. This leaves a channel 3^a into which the plaster 8 45 will be forced to form a retaining bead and leaving the plaster flush with the outer face of the plate. There is thus formed about the inner edge of the plate 1 a slide way to receive the movable plate 5. This plate may 50 be secured in position by first folding the wings at three of the sides and then inserting plate 5 at the open upper or lower edge, after which the remaining wing will be folded to complete the plate 1. The plate 5 55 is adapted to rest against the outer end of the flue thimble 6 which extends from the

chimney to a point slightly within the face of the plastered wall, and it has a central opening registering with the opening of the flue thimble. Within this opening is formed 60 a tubular flange like portion 5^a which fits neatly in the projecting portion of the thimble, and extends preferably into the chimney. This holds the plate 5 in place over the thimble and forms a closure for the 65 opening 4 of the plate 1.

As the building shrinks and settles about the chimney the outer plate will move downwardly about the thimble, thus causing plate 5 to move upward relatively, in its slide 70 way, and relieving the thimble and the plaster of the strain which so frequently destroys them:

The plate 5 will be of a width that will 75 permit it to move in plate 1 a distance equal to the probable amount of shrinkage, and it is also made with a view to keeping the opening 4 closed during such relative movement. The engagement of the tubular portion in the thimble holds the plate 5 fixed 80 with reference to it, preventing its displacement and preserving a neat appearance.

The extent of the oblong opening 4 will be determined by the amount of settling that is likely to occur, and when the settling of 85 the building is complete, the slide plate 5 will stand at its upper limit as seen in Fig. 1. It, of course, will be left at its lower limit, on completion of the building.

It is obvious that the tube 5^a may be a 90 separate piece and not formed integrally as shown.

Having thus described my invention, what I claim, is—

1. A flue thimble protector comprising a 95 main plate having a central oblong opening, a wing extending from each side of the plate and bent inwardly to form a track, each wing being then bent outwardly to form a channel, leaving their edges exposed, 100 and a plate having a thimble engaging means slidably secured in said tracks.

2. A flue thimble protector comprising a main plate having a central oblong opening, a wing extending from each side of the 105 plate and bent inwardly to form a plate retaining flange, whence they are bent outwardly to form a base for said plate, leaving a plaster engaging channel, and a thimble engaging plate slidably secured within the 110 plate retaining flanges.

3. A flue thimble protector comprising a

main plate having a central oblong opening, a wing extending from each side of the plate and bent inwardly to form a plate retaining flange, whence they are bent outwardly to form a base for said plate, leaving a plaster engaging channel, a plate having an aperture adapted to register with the thimble opening slidably secured within the plate retaining flanges, and a tubular ele-

ment secured in the aperture of the sliding plate adapted to engage in the flue thimble.

In testimony whereof I affix my signature in the presence of two witnesses.

VICTOR WESTERLUND.
